UNITED STATES PATENT OFFICE.

NIELS WALTERSEN AASEN, OF COPENHAGEN, DENMARK.

PROPELLER FOR THE PERCUSSION MECHANISM OF VARIOUS PROJECTILES.

1,204,725.

Specification of Letters Patent.

Patented Nov. 14, 1916.

Application filed November 18, 1915. Serial No. 62,164.

To all whom it may concern:

Be it known that I, NIELS WALTERSEN AASEN, a citizen of the Kingdom of Norway, residing at No. 20 Carl Lunds Gade, Copenhagen, Denmark, have invented new and useful Improvements in Propellers for the Percussion Mechanism of Various Projectiles, of which the following is a specification.

10 In naval torpedoes, aviation bombs, quick-burning grenades, and illumination projectiles discharged from tubes, a propelling device is generally used which is joined, either directly or indirectly to the 15 percussion pin or bolt, but always based on the following principle: The air pressure acts on the propeller which thereupon screwing itself into a female thread, releases the striker. By striking upon a priming charge, 20 the latter can then insure the bursting of the projectile upon the latter meeting an obstacle. However, the type of propeller generally used has the following drawbacks: If the dimensioning of the propeller is suffi- 25 ciently great, to enable one to be certain of the striker being released in consequence of the screwing into the female threaded part, even when the projectile is only thrown a short distance, that is to say, when traveling 30 at low velocity, the propeller will oppose a certain resistance when that same projectile will be thrown to a great distance; that is to say, when traveling at a higher velocity. The resistance in question will manifest it- 35 self: 1. By a considerable slowing down of the velocity of the projectile. 2. By a per- turbing action perpendicular to the direc- 40 tion of the projectile, which latter will then assume an erratic movement. In order to avoid both these drawbacks it will be neces- 45 sary to reduce the dimensioning of the pro- peller and then the use of this propeller for throwing grenades at short distances, such as 30 meters (about 32 yards), for instance, 50 can not be thought of. As a matter of fact, giving the grenade too curved a trajectory must not be thought of, and, on the other hand, a certain velocity will be required, in order that the propeller may properly re- lease the striker. On the other hand, the shock will be imparted to the propeller upon the percussing of the projectile; it will therefore be necessary to make it of some- 55 what thick material, whence results a

greater difficulty for its movement in the air. 55 From a manufacturing standpoint, the cost will be increased. That is why an accessory part is sometimes used, the object of which consists in bearing the shock when the projectile percusses. 60

The accompanying drawing shows the de- 65 vice suggested for obviating these several drawbacks.

Figure 1 shows a plan view. Fig. 2 shows a side elevation. 65

The propeller is of conical or pointed shape and made of thin metal. The lower edge of the cone is turned back at right angles to the axis of the propeller and so as to form inclined winglets. The wings are 70 thus bent back at right angles to the axis of the propeller, and slightly turned downward. This particular shape will enable the propeller to offer only a slight resistance when the propeller flies through the air, and, 75 on the contrary, to be highly sensitive to the action of air resistance, to insure the propeller rotating. The working of this type of propeller will therefore be as reliable when the flight of the projectile is at 80 the rate of 10 meters (about 10 yards) per second, as when the speed is 100 meters (about 109 yards) per second. In addition to this, there will be no lateral perturbation of the projectile. Finally, the conical shape 85 increases considerably the propeller's own resistance. It may therefore be made of a thin and light metal, and yet be used for percus- 90 sing direct on the obstacle.

I claim:

1. A propeller for percussion mechanisms for projectiles of the character specified, having a central part of a conical shape, pro- 95 vided with wings bent back at right angles to the axis of the propeller and slightly turned downward.

2. A propeller for percussion mechanisms of projectiles of the character specified, having a central part of a conical shape with wings bent away from the axis of the pro- 100 peller, and slightly turned downward.

In testimony that I claim the foregoing as my invention, I have signed my name in presence of two subscribing witnesses.

NIELS WALTERSEN AASEN.
